UNITED STATES PATENT OFFICE.

WALTER A. LATTIMORE AND WILLIAM V. PARMLEY, OF ST. CLAIR, PENNSYLVANIA, ASSIGNORS TO LATTIMORE MANUFACTURING COMPANY, A FIRM COMPOSED OF HARRY B. DAVIS, THOMAS E. FERREBEE, CHARLES E. BRECKONS, HARRIES L. DADDOW, AND WALTER A. LATTIMORE.

MINER'S CAP AND LANTERN-HOLDER.

No. 839,070.

Specification of Letters Patent.

Patented Dec. 18, 1906.

Original application filed March 18, 1905, Serial No. 250,792. Divided and this application filed June 30, 1905. Serial No. 267,729.

To all whom it may concern:

Be it known that we, WALTER A. LATTIMORE and WILLIAM V. PARMLEY, citizens of the United States, residing at St. Clair, 5 Schuylkill county, State of Pennsylvania, have invented a new and useful Miner's Cap and Lantern-Holder, of which the following is a specification.

Our present invention, which is a division 10 of a pending application, Serial No. 250,792, filed March 18, 1905, for a method of making miners' caps, consists of a novel construction of miners' caps in which a draw-string or equivalent device whereby the size of the 15 cap is adjusted is caused to be retained or concealed within a braid or tape stitched to the bottom of the cap.

It further consists in novel means for providing a separate wall or point of attachment 20 for an end of the draw-string which is preferably on the inside of the miner's lantern-holder secured to the cap, said lantern-holder being so constructed as to provide a means for winding or otherwise securing 25 the end of said draw-string or its equivalent thereon.

It further consists of novel means for securing together the various parts of the lantern-holder or attachment whereby the use 30 of rivets is entirely eliminated and the cost of assembling the parts greatly reduced.

A further object of our invention is the production of a combined miner's cap, means 35 for adjusting the sizes thereof, and means carried by the cap, as on the lantern-holder itself, coacting with the draw-string or equivalent device, whereby the size of the cap can be readily adjusted according to requirements.

To the above ends our invention consists, broadly, in a novel construction of miner's lantern-holder, a cap, and a draw-string attachment therefor, all of which parts coöperate conjointly and wherein the presence of 45 each of these parts is indispensable to effect the necessary operation or coaction of the other parts.

Our invention further consists of other novel features of construction, all as will be 50 hereinafter fully set forth.

Figure 1 represents a perspective view of a finished miner's cap, lantern-holder, and draw-string attachment embodying our invention. Fig. 2 represents a side elevation, partly in section, of a miner's cap and its adjuncts, showing particularly the manner in which the lower portion of the cap is turned up and the manner of attaching the braid, tape, or other device which conceals the draw-string and also the manner of securing 55 and retaining in position the draw-string or equivalent device and the lantern-holder. Fig. 3 represents a front elevation, partly in section, of Fig. 1, a portion of the parts being shown in section on line *z z*, Fig. 2. Fig. 4 60 represents a section on line *x x*, Fig. 1. Fig. 5 represents a section on line *y y*, Fig. 1.

Similar numerals of reference indicate corresponding parts in the figures.

Referring to the drawings, 1 designates the 70 crown of the cap, consisting of the top 2 and side wall 3, stitched together, as at 4, this being preferably done while the cap is turned inside out, at which time the vizor 5 is stitched to the lower portion of the side wall 3. The 75 vizor-cover 6 is now stitched on so that when the cap is turned right-side out the different lines of stitching will not show on the outer side of the cap. The lower edge of the side wall 3 is now turned up on the outside and a 80 piece of braid or tape 7 secured in position, preferably by employing a two-needle sewing-machine, whereby the stitches 8 and 9 are formed simultaneously and at the same time the draw-string 10 is secured in position, 85 as indicated in Figs. 1 to 3, inclusive. As will be apparent from Fig. 3, the termini 11 of the braid or tape 7 are preferably about in the middle of the cap, although of course they may terminate elsewhere. In practice 90 one end of the draw-string 10 is preferably attached or stitched to a suitable portion of the cap or other point, as indicated at 12, while the other free end is secured after the desired adjustment has been effected to a 95 suitable fixed point or abutment, as 13, which is preferably upon the interior of the lantern-holder, fixture, or other attachment 14. In the preferred embodiment of our invention the lantern-holder 14 consists of a 100

forwardly-extending base portion 15, which is preferably made of metal and from which extends at a suitable angle the upright or front piece 16. The outer edges of the base-piece 15 and the upward extension are beaded, as indicated at 17, and serve to retain in position the auxiliary strip of sound-deadening or stiffening material 18. This material 18 is preferably constructed of a suitable fiber, which becomes soft after exposure to the damp air in the mines where these devices usually are employed, said fiber also adding to the strength of the light metal 15. As will be seen in Fig. 1, the fiber 18 after extending upwardly is deflected in a lateral direction, so as to form the top piece 19, which is secured to the cap by rivets or suitable fastening devices 20, while the base-piece 15 is secured to the vizor by rivets or suitable fastening devices 21.

22 designates an eye in the top piece, said eye being located forwardly of the cap at any convenient or desired point and being adapted for the reception of the shank of the lantern-hook usually employed, said shank being prevented from improper movement by means of the slot 23, located in a suitable portion of the top piece.

In the present construction the strip 24, in which slot 23 is contained, is made, preferably, of metal and is located upon the exterior portion of the top piece 19 and projects downwardly, as indicated at 25. The preferred manner of assembling these parts will be understood from Figs. 2 and 3, wherein instead of the rivets heretofore employed we puncture the metal 16, as indicated, at two points 26 and secure the portion 24 in position by means of the downwardly and inturned flanges 27, as seen in Figs. 1 and 4, thereby effecting a great saving in rivets.

As is well known to those skilled in the art or having familiarity with the action of the damp air of mines upon caps and the like, miners' caps invariably shrink to a great extent by reason of this damp air under ground or from perspiration, the amount of shrinkage sometimes being several sizes. By employment of our novel device comprising the cap, lantern-holder, and draw-string assembled in the preferred manner explained, whereby the size of the cap can be speedily adjusted according to requirements, it will be manifest that the size of the cap can be readily varied and a miner can purchase a cap several sizes larger than his head and adjust it according to requirements. It will be apparent that while we have shown and described the adjusting device as being a cord the same can be a strip of braid or tape, or any other equivalent device can be used.

So far as we are aware we are the first in the art to produce as a concrete unitary device a miner's cap having the adjusting device applied thereto in conjunction with the lan-

tern-holder having a portion thereof adapted to coact with said adjusting device whereby the desired results are obtained.

Various changes may be made by those skilled in the art which may come within the scope of our invention.

Having thus described our invention, what we claim as new, and desire to secure by Letters Patent, is—

1. The combination of a miner's lantern-holder, a miner's cap therefor, means for adjusting the size of said cap, and a securing device for said means carried by said lantern-holder. 75

2. The combination of a miner's cap, a lantern-holder therefor, a draw-string carried by said cap for adjusting the size of the latter, and an abutment on said lantern-holder to which said draw-string may be secured. 80

3. The combination of a miner's cap, a lantern-holder therefor, comprising a base-piece, a front piece, a laterally-extending top piece, having an eye and slot therein, means for adjusting the size of said cap, and a fastening device for said means on said lantern-holder. 85

4. A lantern-holder for a miner's cap, comprising a base-piece, an upright extension thereof constituting a front piece, an auxiliary upright piece, adjacent said front piece, and secured thereto, the top of said auxiliary piece being deflected laterally, and a piece on said top piece and secured thereto by inwardly-turned flanges, said top piece having an eye and a slot for the reception of the lantern-hook. 95

5. The combination of a miner's cap, a lantern-holder therefor, a strip secured to the base of said cap, a draw-string within said strip for enabling the size of said cap to be adjusted, one end of said draw-string being secured to a fixed point, and an abutment on said lantern-holder, whereby the other end of said string may be secured in adjusted position. 105

6. The combination of a miner's cap, a top piece made of metal and fiber, the flanges of the metal of said top piece being downwardly and inwardly turned and engaging said fiber 115 on its under side and said top piece projecting from said cap and having an eye and slot therein, a front piece composed of fiber and separate metal from that of the metal of the top piece, the edges of the last side metal engaging the first-mentioned metal, and means for securing said top piece to said cap. 120

7. A lantern-holder for a miner's cap comprising a base-piece, an upright front piece, an auxiliary piece adjacent said front piece 125 and deflected to form a top piece, a metallic strip 24 on said top piece, the latter having an eye therein adapted for the shank of a lantern-hook, and means for preventing said lantern-hook from lateral swinging. 130

8. The combination of a cap, a miner's lantern-holder therefor, means for securing said lantern-holder to said cap, a draw-string constituting an adjusting device on said cap for varying the size of the latter and means on said lantern-holder for securing an end of said adjusting device in desired position.

9. The combination of a miner's cap having a vizor attached thereto, a lantern-holder having its base portion secured to said vizor, an upright portion rising from said base, a strip secured to said cap and having a draw-string constituting an adjusting device, means on said upright portion for securing said string thereto, and a top piece extending laterally from said upright portion, said top piece having an eye and a slot therein.

10. The combination of a cap, a miner's lantern-holder therefor, means to secure said lantern-holder to said cap, a draw-string con-

stituting an adjusting device on said cap for varying the size of the latter, and means for securing the end of said adjusting device in the desired position behind the holder in proximity thereto and adapted to be protected by the holder.

11. The combination of a cap, a miner's lantern-holder therefor, means for securing said lantern-holder to said cap, a draw-string constituting the adjusting device on said cap for varying the size of the latter, and means removed from the body of the cap for securing the ends of said adjusting device in the desired position.
